US0D1016046S

(12) **United States Design Patent** (10) **Patent No.:** **US D1,016,046 S**
(45) **Date of Patent:** **** Feb. 27, 2024**

(54) **MICROPHONE**

(71) Applicant: **Cisco Technology, Inc.**, San Jose, CA (US)

(72) Inventors: **Robert Provo Kluit**, Oslo (NO); **Benoit Rouger**, Espoo (FI)

(73) Assignee: **Cisco Technology, Inc.**, San Jose, CA (US)

(**) Term: **15 Years**

(21) Appl. No.: **29/874,719**

(22) Filed: **Apr. 24, 2023**

Related U.S. Application Data

(63) Continuation of application No. 29/777,830, filed on Apr. 8, 2021, now Pat. No. Des. 989,046.

(51) **LOC (14) Cl.** **14-01**

(52) **U.S. Cl.**

USPC **D14/225**; D14/228

(58) **Field of Classification Search**

USPC ..... D14/225, 228, 227, 229, 216, 149, 140, D14/150, 240, 242, 137, 203.1, 496, 212, D14/219; D13/168; 381/92, 71.1, 160 CPC H04R 25/00; H04R 25/02; H04R 3/00; H04R 1/02; H04R 1/28; H04M 1/20; G09G 5/00

See application file for complete search history.

OTHER PUBLICATIONS

The Chinese Office Action dated Jun. 7, 2023 for Chinese design application No. 202130663565.9, a foreign counterpart of design U.S. Appl. No. 29/777,830, 1 page.

Primary Examiner — Paula Allen Greene

(74) *Attorney, Agent, or Firm* — Lee & Hayes P.C.

(57) **CLAIM**

The ornamental design for a microphone, as shown and described.

DESCRIPTION

FIG. 1 is a top, front perspective view of a microphone; FIG. 2 is a bottom, front perspective view thereof; FIG. 3 is a top view thereof; FIG. 4 is a bottom view thereof; FIG. 5 is a left-side view thereof; FIG. 6 is a right-side view thereof; FIG. 7 is a back view thereof; and, FIG. 8 is a front view thereof.

The dashed broken lines depict portions of the microphone that form no part of the claimed design. The dot-dashed broken lines represent boundaries of the claimed design and form no part of the claimed design.

1 Claim, 8 Drawing Sheets

US D1,016,046 S
